STAPLING MACHINE

George C. Passek, Springfield, Pa., assignor to
Alfred J. Paynter, Philadelphia, Pa.

Application February 24, 1938, Serial No. 192,304

5 Claims. (Cl. 1—49)

This invention relates to improvements in stapling machines wherein instrumentalities are employed for driving the legs of a staple into or through the wall or walls of a packing box or other article, and for bending the staple legs toward each other inwardly of the outer surface of such box or article to fasten the staple therein, such instrumentalities operating and performing their functions wholly on one side of such box or article or exteriorly thereof.

The object of the invention is to provide a novel and advantageous means whereby the legs of a staple, as they are driven into or through the wall or walls of a box or other article, are directed toward each other and caused to assume a curved condition in the plane through which the staple as a whole is driven, thereby fastening the staple within such wall or walls.

The invention resides in the novel construction, combination and arrangement of the elements of the machine as will be hereinafter described and claimed.

In the accompanying drawings, illustrating the invention,

Figure 1 is a central, longitudinal section of my improved machine, on line 1—1 of Fig. 2.

Figure 2 is a vertical section through the forward part of the machine, on line 2—2 of Fig. 1.

Figure 3 is a sectional detail, enlarged, on line 3—3 of Fig. 1.

Figure 4 is a sectional detail, enlarged, on line 4—4 of Fig. 1.

Figure 5 is an enlarged view of the lower portion of Fig. 2, showing the forming member in full view, and showing two layers of material beneath the machine to receive a staple therefrom.

Figure 6 is a vertical section, on line 6—6 of Fig. 5.

Figures 7 and 8 are views similar to Figs. 5 and 6 respectively, showing advanced positions of the parts during a staple driving operation.

Figures 9 and 10 are views similar to Figs. 5 and 6 respectively, showing the positions of the parts at the completion of a staple driving operation.

Figure 11 is a front view of one of the staples.

Figure 12 is a side view of one of the staples.

Referring to the drawings, 5 designates the machine frame having a horizontally-extending lower portion 7 and a vertically-extending forward portion 8 rising from the forward end of the lower portion.

The lower portion 7 of the frame is hollow and it has a floor plate 9 secured thereto and provided with a hollow, longitudinally extending

staple guide 10 for receiving and guiding a row of staples 11.

Slidable in the forward end portion of the staple guide 10 is the rearward extension 12 of a forming member 13 having an inclined forward end surface 14, producing a nose-like forward end portion for the member. This nose-like end portion of the member 13 rests normally within a hollow nose-like projection 15 formed on a plate 16 which is secured to the frame 5 and constitutes 10 the forward wall thereof.

The forming member 13 is urged forwardly and its forward end is pressed normally against the frame plate 16 by a helical spring 17 which encircles a rod 18 having its forward end secured to 15 the forming member 13 and its rearward end portion extending slidably through a block 19 secured upon the floor plate 9. The spring 17 has its forward end engaged with the extension 12 of the member 13, and its rearward end engaged with the block 19.

The row of staples 11 is fed forwardly by a suitable follower 20 which embraces the staple guide 10 and is slidable thereon. The follower 20 has an arm 21 which extends upwardly 25 through a longitudinal slot in the top wall of the lower portion 7 of the frame 5. The arm 21 is connected to one end of a spiral spring 22 which surrounds a pin or shaft 23 and has its other end secured thereto. The pin or shaft 23 extends between and has its ends mounted in openings in the side walls of the forward portion 8 of the frame 5 in a suitable manner to prevent rotation of the pin or shaft. The spring 22 tends to wind itself around the shaft 23 and thereby urges the 30 follower 20 and the row of staples 11 engaged thereby forwardly and presses the foremost staple 35 of the row of staples against the frame plate 24.

The foremost staple 24 embraces the nose-like forward end portion of the forming member 13 40 and its legs 25 occupy positions within oppositely disposed channels 26, 26 on the respective sides of the forming member 13. These channels 26, 26 have parallel guiding walls 27, 27 opposite to the respective sides of the member 13 and 45 spaced therefrom for the reception of the staple legs 25, 25 between them. The forward walls of the channels 26, 26 are formed by the frame plate 16, and the forward surface of the staple next adjacent to the foremost staple 24 constitutes 50 rearward walls for the channels.

Slidably mounted in the forward portion 8 of the frame 5 above and in alignment with the foremost staple 24 is a staple driving plate 28 constructed and arranged to drive the foremost 55

staple 24 downwardly through and discharge it from an opening 29 in the bottom of the machine frame.

The staple driver 28 has a bracket 30 secured thereto and pivoted to the lower ends of a pair of parallel links 31 whose upper ends are pivoted to a lever arm 32 which is fulcrumed, at 33, in the forward portion 8 of the machine frame. The pair of links 31 and the fulcrumed end portion of the lever arm 32 are housed within the machine frame and the free end portion of the lever arm extends out through a slot 34 in the frame and forms a handle 35 which may be lowered and raised to effect staple driving operations.

The staple driver 28 and its operating lever arm 32 are maintained normally elevated by the action of a helical spring 36 acting between a bracket 37 secured to the machine frame and a pin 38 connecting the links of the pair 31. The spring 36 encircles a pin 39 which extends from the pin 38 and is fitted to slide through an opening in the bracket 37 when the arm 32 is lowered against the action of the spring 36 in a staple driving operation. After the staple driving operation, the spring 36 acts to elevate the arm 32 to its normal position.

Deflecting parts 40, 40 for deflecting the staple legs are provided at the lower or delivery ends of the guiding channels 26, 26. The deflecting parts 26, 26 have downwardly and inwardly directed, curved, deflecting surfaces 41, 41 which form, in effect, continuations of the parallel guiding walls 27, 27 of the channels 26, 26; and the parts 40, 40 extend below the bottom of the forming member 13 and they are directed toward each other with their curved deflecting surfaces 41, 41 extending below and spaced from corners or obstructions 42, 42 formed by the member 13 at the junctions of the bottom surface and the side surfaces thereof.

The parallel guiding walls 27, 27 of the channels 26, 26 and the deflecting parts 40, 40 for the staple legs 25, 25 are formed by parallel plates 43, 43 which are vertically adjustable in the machine to raise or lower the deflecting parts 40, 40 with relation to the bottom corners 42, 42, for a purpose presently appearing. The plates 43, 43 are secured in place in different positions of adjustment by shouldered screws 46 which extend through the frame plate 16 and through slots in the plates 43, 43 and secure the plates to the machine frame.

The operation of the machine is as follows:

The machine is placed over the work to be stapled with the bottom surface of the machine in contact with the work, and with the frame opening 29 over the part of the work which is to receive the staple.

The operating arm 32 is then depressed or forced downwardly against the action of the spring 36, thereby forcing the staple driver 28 downwardly and causing it to engage the top of the crown of the foremost staple 24 of the row 11 and drive it downwardly and discharge it through the opening 29 in the bottom of the machine frame.

During the downward movement of the staple 24, it is guided by the channels 26, 26 through which the staple legs 25, 25 move. While the staple 24 is being driven downwardly, its crown engages the forward inclined surface 14 of the forming member 13 and moves the member rearwardly against the action of the spring 17 and between the staple legs 25, 25 until the member 13 has been moved completely out of the path

of the staple crown, as the crown passes the lower end of the inclined surface 14; and, while the staple 24 is thus being driven downwardly, the lower ends of the staple legs 25, 25 encounter the curved surfaces 41, 41 of the deflector parts 40, 40 and are forced between such surfaces and the opposing parts or corners 42, 42 of the forming member 13. As the staple legs 25, 25 are thus forced through the spaces between the surfaces 41, 41 and corners 42, 42, the pressure of the outer surfaces of the staple legs 25, 25 against the channel walls 27, 27 above the corners or obstructions 42, 42 and the pressure of the outer surfaces of the staple legs against the curved surfaces 41, 41 below the corners or obstructions 42, 42 causes the inner surfaces of the staple legs to press hard against the corners 42, 42, and this pressure, coupled with the friction produced by the engagement of the staple legs with the corners, curves the staple legs and directs them inwardly or toward each other within the material 44 of the work or article into which the staple is driven, as clearly shown in Figs. 7, 8, 9 and 10.

After a staple has been driven, as just described, the downward pressure on the handle 32 is removed and the spring 36 raises the handle and staple driver 28 to normal position; and, as the staple driver clears the forming member 13 and the row of staples 11, the spring 17 moves the forming member forwardly to its normal position, and the spring 22 advances the row of staples 11, and moves the foremost staple of the row into position beneath the staple driver 28 for a succeeding staple driving operation.

In Figs. 5 to 10, inclusive, I have shown two layers of the material 44 into which the staple is driven. These layers may constitute meeting parts of a closure for a box or carton into which the staple is driven to secure such parts together; and it will thus be seen that such parts may be secured by a staple or staples driven into the same by instrumentalities which operate and perform their functions wholly on the outside of the box or carton.

The curvature of the metal of the staple connecting the staple legs 25, 25 with the crown 45 thereof permits the inward bending of the staple legs in that region and thereby permits the staple to be forced through the space between the deflecting parts 40, 40, during the completion of the driving movement of the staple, such space being somewhat less than the normal width of the staple before being driven; and this inward bending of the staple legs during the completion of the staple driving movement tends to raise the curved staple legs toward the staple crown and more firmly clamp between them the material into which the staple is driven.

By setting the plates 43, 43 in different positions of vertical adjustment the deflecting parts 40, 40 may be placed closer to or farther from the corners 42, 42 of the forming member 13 the curvature of the legs of the driven staple may be varied, the positioning of the parts 40, 40 closer to the corners 42, 42 effecting a greater curving of the staple legs and setting the legs of the driven staple in closer relation to the staple crown; and the positioning of the parts 40, 40 farther from the corners 42, 42 effecting a lesser curving of the staple legs and setting the legs of a driven staple in a more spaced relation to the staple crown. Thus it will be understood that the machine may be adjusted to accommodate 75

work of different thicknesses between the legs and crown of a driven staple.

I claim:

1. The combination of a frame having parts providing spaced, oppositely disposed channels for receiving and guiding the legs of a staple, a staple driver operable to drive a staple guided by said channels, a forming member having corner portions and movable between the legs of a staple driven by said driver and into the path of the staple crown, said channels having parallel guiding walls opposite to the respective sides of the forming member, and deflecting parts directed toward each other adjacent to said guiding walls at the delivery ends of said channels for cooperation with said walls outwardly of the staple legs and with said corners inwardly of the staple legs for curving said legs and directing them toward each other as they are driven through said channels and between said corners and said deflecting parts.
2. The combination of a frame having parts providing spaced, oppositely disposed channels for receiving and guiding the legs of a staple, a staple driver operable to drive a staple guided by said channels, a forming member movable between the legs of a staple driven by said driver and from and into the path of the staple crown and having an inclined surface to be engaged by the staple crown to move the forming member from its normal position, said channels having parallel guiding walls opposite to the respective sides of the forming member, and deflecting parts directed toward each other adjacent to said guiding walls at the delivery ends of said channels for cooperation with said walls outwardly of the staple legs and with parts of said forming member inwardly of the staple legs for curving said legs and directing them toward each other as they are driven through said channels and between said deflecting parts and said forming member.
3. The combination of a frame having parts providing spaced, oppositely disposed channels for receiving and guiding the legs of a staple, a staple driver operable to drive a staple guided by said channels, a forming member having corner portions and movable between the legs of a staple driven by said driver and from and into the path of the staple crown and having an inclined surface to be engaged by the staple crown to move the forming member from its normal position, said channels having parallel guiding walls opposite to the respective sides of the

forming member, and deflecting parts directed toward each other adjacent to said guiding walls at the delivery ends of said channels for cooperation with said walls outwardly of the staple legs and with said corners inwardly of the staple legs for curving said legs and directing them toward each other as they are driven through said channels and between said corners and said deflecting parts.

4. The combination of a frame having parts providing spaced, oppositely disposed channels for receiving and guiding the legs of a staple, a staple driver operable to drive a staple guided by said channels, a forming member movable between the legs of a staple driven by said driver and from and into the path of the staple crown, said channels having parallel guiding walls opposite to the respective sides of the forming member, and deflecting parts directed toward each other adjacent to said guiding walls at the delivery ends of said channels for cooperation with said walls outwardly of the staple legs and with parts of said forming member inwardly of the staple legs for curving said legs and directing them toward each other as they are driven through said channels and between said deflecting parts and said forming member.

5. The combination of a frame having parts providing spaced, oppositely disposed channels for receiving and guiding the legs of a staple, a staple driver operable to drive a staple guided by said channels, a forming member having side obstructions for engagement by the inner surfaces of the legs of a staple for curving the same, said member being movable between the legs of a staple from and into the path of the staple crown, said channels having guiding walls opposite to the respective sides of said member above the plane of said obstructions for engagement with the outer surfaces of the legs of a staple, and deflecting parts below the plane of said obstructions and directed toward each other adjacent to said guiding walls at the delivery ends of said channels for engagement with the outer surfaces of the legs of a staple, said guiding walls cooperating with said obstructions above the plane thereof, and said deflecting parts cooperating with said obstructions below the plane thereof for curving said legs and directing them toward each other as they are driven through said channels and between said member and said guiding walls and deflecting parts.

GEORGE C. PASSEK.
